LESTER O. BECKER

BY *Lester O. Becker*
ATTORNEY.

UNITED STATES PATENT OFFICE

2,527,114

PRESSING MACHINE

Lester O. Becker, St. Louis, Mo., assignor to
Joseph Pavelka, St. Louis, Mo.

Application September 12, 1947, Serial No. 773,538

15 Claims. (Cl. 164—101)

1

The invention relates to pressing machines of the kind described in Patent No. 2,407,463, issued September 10, 1946, to the present inventor, and has as an object to provide a device whereby a powerful thrust may be exerted with relatively small applied force. The device may be used in various pressing operations, such as punching and bending rails, swaging, forming, cutting and similar operations.

Pressing machines as used heretofore required considerable manual strength to provide a thrust sufficient to punch holes in rails. When the punch broke through the rail, the applied force suddenly was unresisted, and the operator applying the force might fall and be injured. The force applied to the present device when punching rails is so small that when the punch breaks through the rail, the sudden release of the punch is hardly noticeable to the operator.

This and other detail objects of the invention as will appear below are attained by the structure shown in the accompanying drawings which structure is intended to be illustrative, but not exclusive, of other arrangements embodying the general inventive principles.

In the drawings,

Figure 1 is a top view of a portable rail punch embodying the invention.

Figure 2 is a side elevation, partly in section, of the device shown in Figure 1.

Figure 3 is an end view thereof.

Figures 4 and 6 are longitudinal sections taken approximately on the lines 4—4 and 6—6, respectively, of Figure 3 and are drawn to enlarged scale, and

Figure 5 is a transverse vertical section taken approximately on line 5—5 of Figure 2.

The portable rail punch comprises a substantially U-shaped frame 1 provided with a handle 1a and having a screw 2 threaded into one of its legs 1b and mounting a punch 3 for movement towards a die 4 attached to the other leg 1c of frame 1. Punch 3 and die 4 cooperate to punch holes in a rail 5.

Screw 2 may be rotated in either direction by a ratchet 6 comprising a toothed nut 7 rigid with screw 2 and forming the driven member of the ratchet. The driving member of the ratchet includes a body part 8 provided with a circular aperture 9 receiving nut 7 and provided with V-shaped recesses 10 opening off of aperture 9 for receiving pawls 11 and 12. Pawls 11 and 12 are mounted on a rod 13 slidable lengthwise in aligned openings 14 in body parts 8. Pawls 11 and 12 pivot about their inner ends in recesses

2

10 and are urged toward one another by a spring 15. A U-shaped element 13a has its legs extending transversely through rod 13 and engages the opposing faces of pawls 11 and 12 so that when the rod is moved to the position shown in Figure 5, the upper leg of element 13a engages pawl 12 and moves it away from nut 7. At the same time, the lower leg of element 13a releases pawl 11 and permits spring 15 to move pawl 11 into engagement with nut 7. When rod 13 is moved downwardly, pawl 11 will be moved by element 13a out of engagement with nut 7 to permit spring 15 to move pawl 12 into engagement with nut 7 to reverse the direction of operation of the ratchet. An operating arm 16 is rigid with body part 8 of ratchet 6. The structure described is similar to the structure shown in applicant's earlier patent.

Arm 16 is actuated by manual operation of a ratchet 18 anchored to frame 1. Ratchet 18 moves a threaded rod 17 lengthwise and rod 17 is pivoted to arm 16 by a pin 17a. The axis of rod 17 is disposed substantially at right angles to the axis of arm 16, and the axis of ratchet 18 and rod 17 is disposed at substantially right angles to the axis of ratchet 6 and screw 2.

Ratchet 18 is similar to that described above and includes a body part 20 forming the driving member and a nut 19 threaded on rod 17 and forming the driven member. Nut 19 is seated on a ball bearing assembly 21 for rotation relative to a collar 22 having an arm 23 received in a socket 24 in the frame and parallel to the axis of screw 2. Arm 23 is mounted in socket 24 to pivot about its axis and to slide parallel to the axis of screw 2. Body part 20 of ratchet 18 has a rigid operating arm 25. A sleeve 26 has inwardly extending flanges 27, 28 which engage collar 22 and an outwardly extending flange 29 on nut 19, respectively, and maintains assembly 40 of nut 19, ball bearing assembly 21 and collar 22. With this arrangement, ratchet 18 is anchored against movement toward and away from ratchet 6 and its operating arm, but ratchet 18 may pivot about the axis of arm 23 and may move parallel to the axis of screw 2 to accommodate movement of screw 2 relative to frame 1.

By exerting a relatively small force on arm 25 and rotating it in a clockwise direction, indicated by the arrow in Figure 1, nut 19 is rotated in a clockwise direction and moves screw 17 upwardly and rotates ratchet 6 and screw 2 in a clockwise direction, as indicated by the arrows in Figure 3, and advances punch 3 towards die 4. Arm 23 and the associated mecha-

55

nism pivots relative to frame 1 and moves toward frame 1 parallel to screw 2 so that arm 16 and rod 17 are in substantially the same transverse plane.

In the preferred arrangement, the lengthwise travel of rod 17 is sufficient to rotate the driving member of ratchet 6 through an angle equivalent to one tooth. After rod 17 is moved this distance, ratchets 6 and 18 are adjusted for reverse operation and rod 17 and arm 16 are moved in the opposite direction by ratchet 18 without reversing screw 2. After rod 17 is moved downwardly sufficiently for the driving member of ratchet 6 to engage the next tooth on nut 7, ratchets 6 and 18 are adjusted again for forward operation and punch 3 is advanced toward die 4 as described above.

Screw 2 preferably is provided with double threads to increase the strength of the device and to advance die 3 toward punch 4 without excessive operation of ratchet 18. A bar 29 may be inserted through a hole 30 in the end of screw 2 to facilitate adjusting punch 3 relative to die 4 when mounting or removing a rail 5 from the rail punch.

The construction described may be varied substantially without departing from the spirit of the invention, and the exclusive use of those modifications coming within the scope of the claims is contemplated.

What I claim is:

1. In a device of the kind described, a rigid frame, a die seated thereon, a tool opposing said die, a screw device threaded in said frame and arranged to move said tool toward said die, an elongated operating arm for rotating said screw and extending substantially at right angles to the axis of said screw, a screw mechanism operatively connected to said arm and anchored to said frame whereby operation of said screw mechanism operates said arm and rotates said screw and moves said tool toward said die.

2. A device as described in claim 1 in which the longitudinal axes of said screw and said screw mechanism are disposed at approximately right angles to one another.

3. In a device of the kind described, a rigid frame, a die seated thereon, a tool opposing said die, a screw threaded in said frame and arranged for moving said tool toward said die, a ratchet mechanism operatively connected to said screw and including an operating arm, a threaded rod connected to said arm, and means for actuating said threaded rod and anchored to said frame against movement toward and away from said ratchet mechanism.

4. A device as described in claim 3 in which said means pivots relative to said frame and in which said rod and said operating arm are connected for relative pivotal movement and are normally positioned approximately at right angles to one another.

5. In a device of the kind described, a rigid frame, a die seated thereon, a tool opposing said die, a screw threaded in said frame and arranged for moving said tool toward said die, a ratchet mechanism operatively connected to said screw and including an operating arm, a rod connected to said arm, and a ratchet device for actuating said rod longitudinally and anchored to said frame against movement toward and away from said ratchet mechanism, the advance of said screw being less than the advance of said rod.

6. In a device of the kind described, a frame, a die seated on said frame, a pair of screws, a

ratchet operatively connected to each of said screws, one of said screws being threaded into said frame and seating a tool opposing said die, the ratchet of the other screw being anchored to said frame against axial movement and said other screw being arranged for lengthwise movement relative to the frame and operatively connected to the ratchet of the frame threaded screw whereby when said frame anchored ratchet is operated, said frame threaded screw advances relative to said frame and moves said tool toward said die.

7. A device of the kind described comprising a rigid frame, a screw threaded in said frame, a ratchet mechanism to advance said screw in said frame, a member anchored to said frame, a threaded rod associated with said member and being operatively connected to said ratchet mechanism, and means to advance said rod relative to said member to operate said ratchet mechanism and rotate said first mentioned screw in said frame.

8. Structure of the kind described in claim 7 in which the advancing movement of the rod provides for rotation of the screw through an angle equivalent at least to a single advance of the ratchet mechanism.

9. A device of the kind described comprising a frame, a screw threaded in said frame, a ratchet operatively connected to said screw, a rod operatively connected to said ratchet, a member associated with said rod and anchored to said frame against movement towards and away from said ratchet, but pivoted on said frame and movable bodily thereon parallel to the axis of said screw, there being means to advance said rod relative to said member to advance said screw in said frame.

10. A device of the kind described comprising a rigid frame, a screw threaded in said frame and having an arm operatively connected thereto, a threaded rod connected to said arm, a member anchored to said frame and associated with said rod, and means to advance said rod relative to said member to rotate said arm and advance said screw in said frame.

11. In a device of the kind described, a frame, a screw threaded in said frame, an oscillating mechanism operatively connected to said screw to rotate said screw relative to said frame, a threaded rod connected to said oscillating mechanism, a member anchored to said frame against movement toward and away from said oscillating mechanism but movable on said frame parallel to the axis of said screw and also movable about a pivot parallel to said screw axis, an oscillating device threaded on said rod and seated on said member and arranged to advance said rod relative thereto to operate said oscillating mechanism and to rotate said screw relative to said frame.

12. In a device of the kind described, a frame, a screw threaded in said frame, an oscillating mechanism to rotate said screw, a socket in said frame parallel to said screw, an elongated bar received in said socket for movement pivotally and lengthwise of said socket, a mounting on said bar and held thereby against movement toward said screw, a rod connected to said oscillating mechanism, and means associated with said mounting to advance said rod relative to said mounting to actuate said mechanism and to advance said screw in said frame.

13. In a device of the kind described, a frame, a screw threaded in said frame, an oscillating

mechanism operatively connected to said screw to rotate said screw relative to said frame, a threaded rod connected to said oscillating mechanism, means for advancing said rod relative to said frame and anchored to said frame against movement toward and away from said oscillating mechanism, there being means to rotate said screw independently of rotation by said rod.

14. In a press of the class described, a frame, a tool feeding screw threaded therein, an oscillating ratchet for rotating said screw and including an operating arm, a screw for actuating said arm, and an oscillating ratchet supported by said frame for actuating said last-mentioned screw and oscillating said first mentioned ratchet.

15. In a device of the class described, a frame, a tool mounting including a screw threaded on said frame, a ratchet and pawl structure operatively connected to said screw to rotate it relative to said frame and including an actuating lever, a carrier anchored to said frame against movement toward and away from said screw but

movable on said frame parallel to the axis of said screw, a nut rotatable on said carrier with a face opposing a face of said carrier, an anti-friction thrust bearing between said faces, a screw threaded member fitting in said nut and connected to said lever, said nut being operable to advance said threaded member and thereby move said lever to actuate said structure to rotate said screw relative to said frame.
